United States Patent Office.

AMASA HATHAWAY, OF PRAIRIE DU SAC, WISCONSIN.

Letters Patent No. 106,156, dated August 9, 1870.

IMPROVEMENT IN FARM-GATES.

The Schedule referred to in these Letters Patent and making part of the same.

To all whom it may concern:

Be it known that I, AMASA HATHAWAY, of Prairie du Sac, in the county of Sauk and State of Wisconsin, have invented a new and useful Improvement in Farm-Gates; and I do hereby declare that the following is a full, clear, and exact description thereof, which will enable others skilled in the art to make and use the same, reference being had to the accompanying drawing forming part of this specification.

My invention relates to that class of gates for farm and other use which are suspended from hinged or pivoted beams, the latter being so arranged as to be tilted to operate the gate; and

My improvement consists in the construction and arrangement of parts, as hereinafter set forth.

In the accompanying drawing—

Figure 1 is a side elevation;

Figure 2 is a top view; and

Figure 3 is an end view.

Similar letters of reference indicate corresponding parts.

A and B represent the gate-posts, each of which consist of two uprights tied together in any suitable manner, and supported in any suitable manner in or on the ground.

C is a beam, which is pivoted to the post B at the point D.

E represents the gate, which is suspended from the bar C by means of the rods F F, which are attached to the carriage G, the truck-wheels of which rest on and traverse the top of the beam C on a suitable track.

When the beam G is inclined sufficiently, the gate will, by its own gravity, move back and run down on the inclined plane formed by the position of the beam, thus opening the gate. It is closed by inclining the beam in the opposite direction.

The beam is operated by means of the bar H, which is pivoted to the post A at right angles with the beam and gate, as seen in fig. 3.

The forward end of the beam extends through between the uprights, forming the post A, and to it is attached the rod I, which hangs down and is allowed to play up and down freely through the guide J.

K is a rod which is pivoted to the rod I at L, and to the bar H at M.

The bar H being pivoted at the point N to the post A, it will be seen that when the ends of this bar are raised and lowered, the forward end of the beam

C will, by means of the rods I and K, be raised and lowered also, and in this manner the beam C is made to form an inclined plane for opening and closing the gate.

O O represent hanging rods at the ends of the bar H, to take hold of in riding through for operating the bar.

P P represent brace-rods for supporting the beam from the stud R.

S S are brace-rods extending from the top of the post B to the bar H.

T is the casing or box resting on the ground, into which the bottom part of the gate passes when it is opened, and which acts as a guide and protection to it.

It will thus be seen that by simply operating the bar H, by means of the hanging rods O O, the gate is opened and closed.

When closed it is self-fastened by means of the hook U, which catches over a cross-piece, V, in the post A. The act of opening necessarily unfastens it.

X X are two guide-wheels supported on stands at the foot of the post B, for keeping the bottom of the gate in place and preventing friction against the post and casing T.

The rollers of the carriage G are grooved and run on the edge of a plate, Y, which is attached to the side of the beam C.

These gates, and the parts connected therewith, may be made of either wood or iron, or partly of wood and partly of iron, as may be deemed most advisable.

I am aware that two hinged horizontal beams for supporting a gate, and an arrangement of separate levers for opening and closing the latter, are in use; but my invention does not pertain to these.

Having thus described my invention,

I claim as new and desire to secure by Letters Patent—

In combination with the gate E F G and the beam C, centrally pivoted on the post B, the bar H, when connected with said beam by rods K, and pivoted centrally to the post A, all constructed and arranged and operating as shown and described.

AMASA HATHAWAY.
